UNITED STATES PATENT OFFICE.

ALFRED S. ORCHARD, OF PHILADELPHIA, PENNSYLVANIA, ASSIGNOR TO KEYSTONE TYPE FOUNDRY, OF PHILADELPHIA, PENNSYLVANIA, A CORPORATION OF PENNSYLVANIA.

PRINTER'S GALLEY.

1,209,328.

Specification of Letters Patent. Patented Dec. 19, 1916.

Application filed February 21, 1916. Serial No. 79,605.

To all whom it may concern:

Be it known that I, ALFRED S. ORCHARD, a citizen of the United States, residing at Philadelphia, Philadelphia county, and State of Pennsylvania, have invented and discovered certain new and useful Improvements in Printers' Galleys, of which the following is a specification.

My said invention consists in an improved construction of printers' galleys, relating particularly to the end thereof, which is constructed to be readily removable and, at the same time, to be securely locked in position and aid in supporting the sides of the 15 galley in proper form, all as will be herein-after more fully described and claimed.

Referring to the drawings in which like reference characters indicate similar parts, Figure 1 is a perspective view of a printer's 20 galley constructed in accordance with my said invention, Fig. 2 a cross section on the dotted line 2—2 in Fig. 3, Fig. 3 a longitudinal section on the dotted line 3—3 in Fig. 2, and Fig. 4 a perspective view of the removable end separately, as seen when looking into the underside thereof.

In said drawings the portions marked A represent the body or floor of the galley, and B the frame of the removable end.

The body A of the galley is made preferably of a single sheet of metal having its sides *a* first doubled over and then bent upwardly at right angles therewith, forming crimps or beads 10 along the edges of the 35 galley, composed of the doubled metal, serving the two-fold purpose of stiffening the sides and enabling them to stand perpendicularly in relation to the floor without an angle at the corner to interfere with the perpendicular set of the type. The end member B is likewise formed of a sheet of metal of appropriate thickness, stamped in the form shown. The front and rear sides thereof 40 and 12 are bent downwardly at right angles with the top, and the projecting end 20 of flange 11 is bent in to stand parallel with one side *a* of the galley, while its other end 21 is bent in to stand parallel with the other side *a* of the body, the two ends thus supporting said sides *a* against inward bending. The outer ends of the top of the plate are bent downwardly at right angles, forming flanges 13 which are spaced from ends 20 and 21 to fit over the edges of the sides *a* of the 45 galley, forming narrow ways between

their inner faces and the outer faces of said ends, thus serving to support said side pieces from spreading. In the top of said end member B a recess is formed by cutting appropriate slits and bending down two parts 60 to form depending flanges 14. A perforation is formed in each of said flanges and in the end flanges 20 and 21, in which locking pins 15 are mounted to slide. Said locking pins 15 are formed with handle members 16 65 projecting at right angles therefrom, by which they may be operated with the thumb and finger of the hand. Coiled springs 17 are interposed between pins 18 and the flanges 14 and serve to normally hold said pins outwardly. Perforations 22 are formed in the sides of the galley, near each end, into which these locking pins are adapted to be inserted. Notches 23 are formed in one side of member B to receive and lock handle 75 member 16 when the galley is in condition for use.

In operation, the operator, by the thumb and finger, presses the members 16 together, compressing the springs 17 and drawing the 80 ends of the locking pins 15 flush with the outer surface of the in-turned ends of the side pieces of the end member B. The end member is then placed in position, with the flanges 13 overhanging the sides *a* of the 85 galley, and slid to a position where the locking pins will register with the perforations 22 at either end. The springs 17 are then allowed to expand, forcing the locking pins 15 into said perforations and securing said 90 end member from further movement.

This construction provides a rigid end, but one that can be readily removed or shifted from one end to the other of the galley, or adjusted by forming the perforations 22 at such points as may be desired.

Having thus fully described my said invention, what I claim as new and desire to secure by Letters Patent, is:

1. A printer's galley comprising a body 100 member with sides upturned at right angles with the floor thereof, and an end member formed to fit between said sides and slide freely lengthwise of said galley and also formed with flanges overhanging the top 105 edges of said body member which serve to guide said end member and connect the same with said body member and prevent the spreading of the sides of said body member, and means for locking said end member in 110

adjusted position on said body member, substantially as set forth.

2. A printer's galley comprising a body member having side portions upturned at 5 right angles with the floor thereof, an adjustable end piece therefor constructed of sheet-metal and having side portions in-turned to fit between the side portions of the body and with overhanging flanges on its 10 top adapted to hang over the outside of said body portions, the space between the in-turned end portions and the overhanging flanges forming ways to receive the top edges of said body side portions and also 15 serving to support said side portions from spreading, and means for locking said end member in adjusted position, substantially as set forth.

3. A printer's galley comprising a body 20 member having side portions, an adjustable end piece therefor constructed of sheet metal having side portions with in-turned ends adapted to fit between the adjacent faces of the side portions of said body and a top portion with downwardly disposed flanges at 25 the ends and intermediate said ends, and spring tensioned locking pins mounted on

said intermediate flanges and the in-turned end portions adapted to engage the side portions of the body member and secure the end 30 piece in position, substantially as set forth.

4. A printer's galley comprising a body member having side portions, an adjustable end piece therefor constructed of sheet metal having a side portion with in-turned ends, 35 and a top portion with downwardly disposed flanges at the ends and intermediate said ends, said side portion provided with notches; and a pair of spring tensioned locking pins mounted on said intermediate flanges and the in-turned ends for securing the end piece to said body member, said pins having portions adapted to engage within 40 said notches to lock the pins in adjusted position, substantially as set forth.

In witness whereof, I have hereunto set my hand and seal at Philadelphia, Pennsylvania, this 11th day of February, A. D. nineteen hundred and sixteen.

ALFRED S. ORCHARD. [L.S.]
